By

UNITED STATES PATENT OFFICE.

JOHN A. SOUTHWELL, OF SCRANTON, PENNSYLVANIA.

SPADE OR SHOVEL.

1,352,921.

Specification of Letters Patent. Patented Sept. 14, 1920.

Application filed April 24, 1919. Serial No. 292,418.

To all whom it may concern:

Be it known that I, JOHN A. SOUTHWELL, a citizen of the United States, residing at Scranton, in the county of Lackawanna and 5 State of Pennsylvania, have invented new and useful Improvements in Spades or Shovels, of which the following is a specification.

This invention relates generally to hand 10 operated digging implements, and particularly to spades or shovels, its primary object being to provide improved means for connecting the shank of the implement to the blade portion thereof.

15 A further object of the invention is to provide a spade having its shank and step portions so constructed and arranged as to overcome the possibility of the step portions becoming loose or accidentally removed from the blade or shank.

20 A further object is to provide improved means for connecting the shank portion with the blade, further characterized by means whereby the blade is reinforced and 25 strengthened at that part which bears the greatest strain during the digging or shoveling operation.

With these objects in view, together with others which will appear as the description 30 proceeds, the invention resides in the novel construction, combination and arrangement of parts, all as will be described more fully hereinafter, illustrated in the drawing and particularly pointed out in the claims.

35 In the drawing:—

Figure 1 is a front elevation of a spade or shoveling implement constructed in accordance with the invention,

40 Fig. 2 is a rear elevation of the improved spade,

Fig. 3 is a longitudinal sectional view taken through the spade,

45 Fig. 4 is a similar view with the shank in the position it will assume before being applied to the blade,

Fig. 5 is a front elevation of the blade forming a part of the invention,

Fig. 6 is a top edge view of the blade,

50 Fig. 7 is a transverse sectional view taken through the spade and showing the manner in which the blade gripping portions engage upon the front and rear faces of the blade, and

Fig. 8 is a transverse sectional view taken through the shank and illustrating the reinforcing web therein.

Referring now more particularly to the drawing, 9 indicates generally the shank constituting the means for connecting the blade to the handle, and this shank, which 55 is of tube formation, receives the ordinary wooden handle at its upper end. The shank may be of cast metal, and to reinforce or strengthen the same at the curved portion thereof, to which the greatest strain and 60 pressure are subjected, a web 10 is formed upon the interior of the shank and extends lengthwise thereof throughout the extent of 65 the curved portion.

The lower extremity of the shank is provided with blade engaging or gripping portions 70 11 and 12. These portions engage upon the front and rear faces of the blade and firmly hold the latter in proper position upon the shank.

75 The steel blade of the spade is indicated generally at 13, and is provided at its upper edge and near the outer edges thereof with lugs or tongues 14. The blade at its upper end and intermediate its lateral edges is deformed as indicated at 15, in the drawing, the deformed portion being of substantially triangular or V-shape. This deformed portion is provided with a central relatively large opening 16 and near its corners is provided with smaller openings 17, the said openings receiving studs or lugs 18 and 19 formed integral with the rear gripping portion 12 of the shank. The stud 18 extending forwardly from the said rear gripping 80 portion passes through the central opening 16 in the blade and also through an opening in the front blade engaging portion 11 of the shank, and the forward end of this stud after passing through these thicknesses may 85 be ironed down or upset so as to prevent the same becoming disengaged from the front blade gripping member. The studs 19 project through the openings 17 in the blade and are similarly upset or headed at their 90 forward ends to prevent the blade becoming detached from the engaging or gripping portion.

95 As shown in the transverse sectional view, the under face of the forward blade engaging portion 11 is shaped so as to conform to 100

the angle of inclination and transverse contour of the deformed portion 15 and to lie snugly upon such portion. This front blade engaging portion 11 is therefore arranged 5 at an oblique angle to the plane of the blade and provided upon its under face with a groove of substantially V-shape, and into which the apex of the V-shape deformed portion 15 engages. It will be observed 10 that the rear blade engaging portion 12 is of triangular form or V-shaped and provided with a rearwardly deflected longitudinally extending offset 12'. This member 12 is of such size as to fit within and have its 15 body portion conform to the concaved rear face of the offset or deformed portion 15 of the blade, whereby the blade is doubly reinforced at its point of attachment to the shank and the portion 12 also stayed against 20 possibility of shifting and straining the fastening rivets. Furthermore, it will be observed that the central longitudinal offset 12' of part 12 is arranged in the plane of the blade, but is spaced from and arranged 25 at an oblique angle to the portion 15, the said parts relatively converging in a downward direction and forming a triangular bracing reinforcing the blade longitudinally and in a direction from front to rear 30 of the blade.

The shank is provided with laterally disposed step portions 20, the latter being cast or formed integral with the shank, and these steps are provided near their outer ends with 35 openings to receive the upstanding lugs or tongues 14 on the blade. The step portions are of such width as to cover entirely the upper edge of the blade, so that it will be impossible for the foot of the operator to 40 contact the relatively sharp upper edge of the blade. The lugs or tongues 14 which protrude through the openings in the step members are headed or ironed down so as to prevent the said lugs becoming detached 45 from the step portions, and these heads may be sufficiently smooth as not to form an obstruction for the foot of the operator.

Before applying the blade to the shank portion, the forward or front blade engaging portion 11 is moved forwardly to the 50 position shown in the detail view. After the blade has been inserted between these gripping portions and the lugs 14 thereof are engaged in the openings in the step members, the blade engaging portion 11 is 55 pressed rearwardly until it is in firm contact with the deformed portion 15 of the blade. When in such position, the stud 18 will protrude through the said blade engaging portion 11, and the forward end of 60 this stud may then be upset or headed. The forward ends of the studs 19 will then also be headed, as will be the upper ends of lugs or tongues 14. The blade will then be firmly 65 secured to the shank portion with its upper

edge fitting firmly beneath the step portions 20. It will be noted that the stud members are headed only upon their forward ends, so that the rear surface of the shovel or spade will have no heads or rivets to become worn off and offer obstruction to the digging operation. By connecting the blade with the shank member in the manner specified, great strength and rigidity are assured, and the particular formation of the blade 70 engaging portions and the blade at its point of connection with such portions reinforces the shovel or spade in the place where the greatest strains and stresses are applied.

While the above is a description of the 80 preferred embodiment of the invention, it is obvious that various changes in the details of construction may be resorted to without departing from the spirit of the invention as defined by the claims. 85

Having thus fully described my invention, I claim:—

1. In a spade or shovel, a blade having a central, substantially V-shaped forwardly offset deformed portion at the upper end 90 thereof, a shank having front and rear blade engaging portions, said front blade engaging portion being arranged to overlie the front surface of the deformed portion of the blade and the rear blade engaging portion being substantially of triangular form and arranged to fit within the concavity at the rear side of said concaved portion, said rear blade engaging portion being provided with a rearwardly projecting longitudinally extending stiffening offset disposed in alignment with the rear surface of the body of the blade, the said blade engaging portions of the shank being arranged to extend downwardly in convergent relation 100 to each other, fastening means connecting the body portion of the rear blade engaging portion of the shank with the deformed portion of the blade, and fastening means connecting the offset of said rear blade engaging portion of the shank with the deformed portion of the blade and the said front blade engaging portion of the shank. 110

2. In a spade or shovel, a shank comprising a tubular member, step portions formed integral with said member and projecting laterally therefrom, blade engaging portions formed integral with said shank, and a web upon the interior of said tubular member for reinforcing the same. 115

3. In a spade or shovel, a shank, a blade, a deformed portion at the upper end of said blade, blade engaging portions formed integral with said shank and adapted to confine the blade between them, the said portions conforming to the shape of the deformed portion of the blade, and studs carried by one of said portions and extending through the blade. 125

4. In a spade or shovel, a shank, spaced 130

blade engaging portions formed integral with said shank, a blade, a deformed portion of substantially V-shape at the upper end of said blade, said blade being adapted to be confined between the said engaging portions at its deformed portion, studs on one of said portions to extend through the

deformed portion, step members formed integral with said shank and projecting laterally therefrom, and lugs upon the blade to 10 extend through the said step members.

In testimony whereof I affix my signature.

JOHN A. SOUTHWELL.
